UNITED STATES PATENT OFFICE

164,554

AUTOMATIC PRESSURE COOKER STAND

Donald E. Dailey, Evansville, Ind., assignor to
Proctor Electric Company, Philadelphia, Pa.,
a corporation of Pennsylvania

Application December 23, 1950, Serial No. 13,555

Term of patent 14 years

(Cl. D44—29)

To all whom it may concern:

Be it known, that I, Donald E. Dailey, a citizen of the United States of America, residing in Evansville, Vanderburgh County, Indiana, have invented a new, original, and ornamental Design for an Automatic Pressure Cooker Stand, of which the following is a specification, reference being had to the accompanying drawings, forming part thereof, in which:

Fig. 1 is a side elevational view of the automatic pressure cooker stand;

Fig. 2 is a front elevational view of the device;

Fig. 3 is a plan view of the device;

Fig. 4 is a rear elevational view of the device;

Fig. 5 is a sectional view taken along line 5—5 of Fig. 2;

Figs. 6 and 7 are perspective views of the device taken from different positions; and

Fig. 8 is an enlarged fragmentary perspective view of the pressure-selection portion of the device.

The pressure cooker shown in dot-and-dash lines in Fig. 1 is for illustrative purposes only.

The heating element with vessel-operated switch in dash lines in Figs. 1, 2, 3, 6 and 7 are for illustrative purposes only.

The novel features of the design are shown by the solid line portions of the drawings.

I claim:

The ornamental design for an automatic pressure cooker stand, substantially as shown and described.

DONALD E. DAILEY.
